(57) **CLAIM**

I claim the ornamental design for a t-block partition or barrier mount, as shown and described.

DESCRIPTION

FIG. 1 is a perspective view of a t-block partition or barrier mount;

FIG. 2 is a front view of the t-block partition or barrier mount of FIG. 1;

FIG. 3 is a back view of the t-block partition or barrier mount of FIG. 1;

FIG. 4 is a left side view of the t-block partition or barrier mount of FIG. 1;

FIG. 5 is a right side view of the t-block partition or barrier mount of FIG. 1;

FIG. 6 is a top view of the t-block partition or barrier mount of FIG. 1;

FIG. 7 is a bottom view of the t-block partition or barrier mount of FIG. 1;

FIG. 8 is an alternate perspective view of the t-block partition or barrier mount of FIG. 1;

FIG. 9 is an environmental view of the t-block partition or barrier mount of FIG. 1; and,

FIG. 10 is an alternate environmental view of the t-block partition or barrier mount of FIG. 1.

The broken lines are shown for the purpose of illustrating environmental subject matter and form no part of the claimed design.
